UNITED STATES PATENT OFFICE.

JOHN F. O'CONNOR, OF CHICAGO, ILLINOIS, ASSIGNOR TO WILLIAM H. MINER, OF CHAZY, NEW YORK.

DRAFT-RIGGING FOR RAILWAY-CARS.

1,258,936.

Specification of Letters Patent. Patented Mar. 12, 1918.

Application filed March 1, 1916. Serial No. 81,332.

To all whom it may concern:

Be it known that I, JOHN F. O'CONNOR, a citizen of the United States, residing at Chicago, in the county of Cook and State of Illinois, have invented a certain new and useful Improvement in Draft-Rigging for Railway-Cars, of which the following is a full, clear, concise, and exact description, reference being had to the accompanying drawings, forming a part of this specification.

This invention relates to improvements in draft rigging for railway cars.

The object of my invention is to provide a draft rigging of efficient operation and durable construction.

In the drawing forming a part of the specification, Figure 1 is a side elevation partly in central vertical, longitudinal section of 20 a draft rigging embodying my invention. Fig. 2 is a horizontal section taken on line 2-2 of Fig. 1, except that in Fig. 2 the parts are positioned as in full compression of the gear, while the parts in their normal 25 position are illustrated in Fig. 1. Fig. 3 is a cross section taken on line 3-3 of Fig. 1. Fig. 4 is a cross section taken on line 4-4 of Fig. 1. Fig. 5 is a perspective view of a wedge. Fig. 6 is a perspective view of 30 a plunger member.

Referring to the drawings, the numerals 1-7 indicate draft members or parts of the car frame to which the draft rigging is applied, 8-8 front stop members and 9-9 rear stop members, the said stop members being secured to the draft members by suitable means, preferably rivets 10-10. The stop members are provided with stop shoulders 11-11, which serve their usual functions, and the front stop member is preferably provided with the limiting stop shoulders 12-12. A draft gear 13 is mounted between the draft members and operatively connected to the draw bar 14 by means of 45 the draft yoke 15, which is keyed to the draw bar by the coupler key 16, the said coupler key passing through the slot 17 in the draw bar, through the elongated slots 18 in the draft yoke, and extending at its 50 end through the elongated slots 19, in the front stop members and adjacent portions of the draft members. The draft gear comprises the shell 20, which is preferably a hollow cylinder in form and having at its

end the integral rear follower member 21, 55 and further comprises the contained friction members 22 and spring members 23. A front follower is indicated at 24. The numeral 25 indicates a tie plate secured to the draft members by suitable means, preferably the bolts 26, which serves as a support for the draft gear. The friction members of the draft gear include a wedge 27, front and rear sets of friction shoes 28 and 29, respectively. Each set of friction shoes 65 comprises preferably three shoes in annular arrangement, the arrangement of the front set being clearly shown in Fig. 3, and that of the rear set being shown in Fig. 4 of the drawings. Each of the friction shoes is 70 provided with an outer friction face 128, which engages the internal friction surface 129 of the shell and is also provided with an inner wedging face 30 against which an anti-friction roller 31 is mounted. Each of 75 the said rollers is seated against an opposed wedging face provided upon the wedge 27. The wedge, it will be observed in Fig. 5, is a block having the front set of wedging faces 32 thereof and the rear set of wedging faces 33 at its inner end. The wedging faces of the front set and of the rear set are staggered in reference to each other and in preferable arrangement the faces of one set are in a position substantially 60° removed 80 from the longitudinal axes of the wedging faces of the other set. The shoes of the front set of friction shoes and those of the rear set are similarly arranged. The shoes of the rear set are so constructed as to provide spaces 35-35 between them adapted 85 for the passage of the legs 36-36 of the plunger member 37, which is shown in perspective in Fig. 6 of the drawings. The said plunger member 37 is provided with a collar 95 38, the inner faces 39 of which are, in normal position of the gear, adjacent the inner ends 40 of the rear set of shoes. The legs 36 extend forwardly through the spaces 35-35, and at their ends 41 engage the rear 100 ends 42 of the friction shoes of the front set. The spring members of the gear comprise an outer spring 44 which is seated at its rear end against the inner face of the shell and at its forward end against the 105 collar 38 of the plunger member 37, and further consists of an inner spring 45 rearwardly seated against the shell and for-

- wardly seated against the washer 46, which engages the shoulders 47—47 provided upon the inner faces of the friction shoes of the rear set. A connecting bolt 48 passes through the wedge 27, the washer 46 and the rear end of the friction shell, and is provided with a head 50, seated within the depression 51 at the rear end of the shell, and a nut 52 seated within the recess 53 with 10 which the forward end of the wedge 27 is provided. On rearward movement of the draw bar in buffing action of the rigging, the coupler key slides rearwardly in the slots in the draft members and front stop 15 member, the front follower 24 is forced rearwardly, the shell is held against rearward movement by the rear stop member and the wedge against which the front follower engages is forced rearwardly, the rearward 20 movement being resisted by the action of the inner spring against the rear set of shoes and of the outer spring against the forward set of shoes and by the frictional engagement of the shoes against the shell under 25 the spreading action of the wedging member. On forward movement of the draw bar the yoke draws the draft gear forwardly, the front follower is stopped against forward movement by the front stop 30 shoulders and the wedge is held against forward movement, the action of the compression resisting elements within the shell being the same as in buffing movement when the shell is stationary. The arrangement 35 of wedge and shoes described herein, permits a wider distribution of the spreading force of the wedge than is obtained through the employment of one set of shoes alone, and by reason of the staggered arrangement 40 of the shoes an even frictional bearing is secured, and by the employment of the plunger member and the particular arrangement described, I am permitted to forwardly mount two compression resisting 45 units, each consisting of a wedge, friction shoes, and resisting springs within a one chambered shell.
- These and many other advantages will be apparent from the foregoing description 50 and from the drawing.
- I claim:
1. In a friction draft gear, the combination with a friction shell, of a pair of tandem arranged sets of friction elements co-operable with said shell, each set including a plurality of friction shoes and a central wedge; and a spring for each set of said friction elements for individually resisting the movements of the latter.
  2. In a draft gear, a shell, a plurality of sets of friction shoes alined therein, springs to resist the inward movement of said shoes, a spreading member for the shoes, the spreading member being provided with a plurality of sets of wedging faces, the faces
- of one set being staggered in their position in reference to the faces of another set.
3. In a draft gear, the combination with a shell, of front and rear sets of friction shoes, a spreading member for said shoes, a spring mounted to resist the movement of the inner set of shoes, a plunger member engaging the front set of shoes, and a spring to resist the inward movement of the said plunger member.
  4. In a draft gear, a shell, front and rear sets of friction shoes within the shell, a spreading member therefor, an inner spring to resist the inward movement of the rear set of shoes, an outer spring to resist the inward movement of the front set of shoes, the action of the said spring being transmitted to the front set of shoes by means passing between the shoes of the rear set.
  5. In a draft gear, a shell, front and rear sets of friction shoes therein, a wedge to spread said shoes, a spring member to resist the inner set of shoes, a further spring member to resist the outer set of shoes, and a plunger member, the plunger member engaging the last mentioned spring at one end and the front set of shoes at the other end.
  6. In a draft gear, a shell, front and rear sets of friction shoes therein, a wedge to spread said shoes, a spring member to resist the inner set of shoes, a further spring member to resist the outer set of shoes and a plunger member, the plunger member engaging the last mentioned spring at one end and the front set of shoes at the other end, the said plunger member comprising a collar engaging the spring, and legs extended therefrom to engage the front set of shoes.
  7. In a draft gear, a shell, front and rear sets of friction shoes therein, a wedge to spread said shoes, a spring member to resist the inner set of shoes, a further spring member to resist the outer set of shoes and a plunger member, the plunger member engaging the last mentioned spring at one end and the front set of shoes at the other end, the said plunger member comprising a collar having legs passing between the shoes of the rear set.
  8. In a draft gear, a shell, front and rear sets of friction shoes in said shell, springs to resist said shoes, a wedge to spread said shoes and anti-friction rollers mounted between the shoes and the wedge, the rollers engaging the rear set of shoes being staggered in their position in relation to the rollers engaging the front set of shoes.
  9. In a draft gear, the combination with a cylindrical shell, of springs, and a plurality of sets of annularly arranged friction shoes within the shell, a plunger member having legs passing between the shoes of the rear set and engaging the shoes of the

adjacent set, a spring member seated against the plunger and a further spring member seated against the rear set of shoes.

10. In a draft gear, in combination, a shell, a plurality of sets of friction shoes within the shell, a wedging member for each of said sets, spring members to resist the inward movement of the friction shoes, a plunger member, and anti-friction rollers, the anti-friction rollers being arranged in sets equaling in number the sets of friction shoes, the bearing faces for the said rollers between the wedging members and shoes being staggered in one set in reference to the adjacent set.

11. In a draft gear, the combination with a shell having a single chamber for receiving the compression resisting elements, of a plurality of sets of friction shoes, each set being provided with a separate spring to resist the inward movement thereof within the shell.

12. In a friction draft gear, the combination with a friction shell, of a plurality of sets of friction elements arranged one behind the other, each set including a plurality of friction shoes and a wedge; a spring for each set of said friction elements for individually resisting movements of the latter, said sets of friction elements being angularly offset with respect to each other.

13. In a draft gear, in combination, a shell, front and rear sets of friction shoes therein, a plunger member and springs, the plunger member having a collar adjacent the rear ends of the rear set of friction shoes and legs engaging the front set of friction shoes, one of the springs being seated

against the collar of the plunger member, another spring passing through the said collar and being seated against the rear set of friction shoes.

14. In a draft gear, in combination, a shell, front and rear sets of friction shoes therein, a spreading member therefor, a plunger member engaging the front set of shoes at one end and extending beyond the rear set of shoes at the other end, a spring seated against said plunger member, a washer seated against the rear set of friction shoes forwardly of the rear end of the plunger member, and a spring seated at its forward end against said washer.

15. In a draft gear, a shell, a plurality of sets of friction shoes therein, a wedge within the shoes having a plurality of sets of wedging faces thereon, there being one set for each set of friction shoes, each set of friction shoes being provided with a separate spring to resist the inward movement thereof.

16. In a friction gear, the combination with a friction shell, of two sets of friction mechanisms coöperable therewith, each set including a spreader and a plurality of friction shoes, the wedge faces of one set of friction mechanism being angularly offset relatively to those of the other set, and spring means for resisting movement of each of said sets of friction mechanisms relatively to the shell.

In witness that I claim the foregoing I have hereunto subscribed my name this 31st day of Jan. 1916.

JOHN F. O'CONNOR.
